2,676,405

CUTTER, PARTICULARLY ADAPTED FOR
THE USE IN CUTTING WALL COVERINGS

Fred Schierhofer, Tuckahoe, N. Y.

Application July 3, 1951, Serial No. 235,049

3 Claims. (Cl. 30—293)

1

The present invention relates generally to cutting devices, and is particularly directed to wall-paper cutters or trimmers of the kind employing a razor blade or other similar cutting element.

When wall-paper or other sheet covering is affixed to a wall it is necessary to trim the paper or sheet covering along the edges adjacent to the wood work, such as, door frames, window frames, base boards and ceiling mouldings, as well as in corners where walls are joined. In trimming wall-paper as above, it is desirable that the cutting blade be prevented from cutting into the underlying wall to thereby protect the wall from damage, and also to increase the period during which the cutting blade retains its sharpness. If penetration of the wall by the cutting blade is to be avoided, the paper, in the immediate area being cut, must be spaced from the wall so that the blade may cut through the paper alone. In trimming the edges of wall paper adjacent to wood-work of various kinds or along the corners where other walls meet the wall to which the paper is being applied, it is desirable that the adjacent wood-work or meeting wall be used as a guide for the cutting blade without contacting the latter, which contact would dull the cutting edge. Finally, it is desirable that provision be made for adjusting the position of the cutting blade relative to the guide member so that the latter may be engaged with the adjacent wood-work or meeting wall at either side, above or below the cutting blade.

It is therefore an object of the present invention to provide a wall-paper cutting or trimming device for holding a cutting blade in a manner to trim the edges of wall-paper or the like without penetrating or damaging the underlying wall surface, and which is guided by contact of the device with the adjacent wood-work or meeting wall, with the blade itself being protected against dulling contact with the guiding wood-work or meeting wall.

Another object is to provide a wall-paper cutting or trimming device in which the cutting blade is supported relative to the wall by a laterally rounded guide member so that the paper may stand away from the underlying wall in the immediate area being cut, and in which the guide member is adjustable relative to the cutting blade so that the latter may be arranged close to the wood-work or meeting wall engaged by either side of the rounded guide member.

Finally, an object of this invention is to provide a wall-paper cutting or trimming device of the character described above which is simple and sturdy in construction.

2

With these and other objects, features and advantages which will appear as the description proceeds in view, the present invention consists in the combination, arrangement and details of construction of the several parts of the device hereinafter described and illustrated in the accompanying drawing, and then more particularly defined in the appended claims.

In the accompanying drawing, wherein the same reference numerals are used to designate the same parts in the several views:

Fig. 1 is a side elevational view of a wall-paper cutting device embodying the present invention;

Fig. 2 is a front elevational view of the wall-paper cutting device of Fig. 1;

Fig. 3 is a top plan view partly broken away of the illustrated cutting device;

Fig. 4 is a bottom plan view, partly broken away, of the illustrated wall-paper cutting device;

Fig. 5 is a front elevational view, similar to Fig. 2, but showing the guide member in an adjusted position relative to the cutting blade to dispose the latter for cutting wall-paper along an adjacent length of wood-work or a meeting wall;

Fig. 6 is a front elevational view, similar to Fig. 5, but showing the guide member in another adjusted position relative to the cutting blade to dispose the latter for cutting wall-paper along an adjacent length of wood-work or a meeting wall, shown in section, at one side of the device;

Fig. 7 is a front elevational view, similar to Fig. 6, but showing the guide member in the adjusted position of Fig. 5 for cutting wall-paper along a length of wood-work or a meeting wall, shown in section, at the side of the device opposite to the location of the wood-work or meeting wall in Fig. 6; and

Fig. 8 is a side elevational view, looking in the direction of the arrows 8—8 of Fig. 6, and showing the cutting device in cutting position.

Referring to the drawing in detail, and initially to Figs. 1 to 4 thereof, a cutting device, embodying the present invention, is there shown and generally indicated by the reference numeral 10. The cutting device 10 includes a suitably shaped handle 11 having a cutting-blade holder 12 formed to removably hold a cutting-blade 13 which is preferably in the form of a single-edged razor blade. The holder 12 forms a channel opening along the bottom edge 14 and at the end adjacent the handle 11 to slidably receive the spine or head of the razor blade 13 with the cutting edge portion of the latter extending through the bottom edge 14. The holder 12 is formed so that the edge 14 thereof is angularly related to

the longitudinal axis of the handle 11 to thereby permit insertion and removal of the cutting blade through the end of the holder 12 adjacent the handle without interference from the latter. The angular relationship of the holder and handle further permits cutting engagement of the blade 13 with wall-paper while positioning the handle 11 remote from the wall to which the paper is applied (Fig. 8) so that the handle may be conveniently grasped.

The cutting device 10 according to this invention further includes an assembly for supporting the device relative to the wall so that the latter is not penetrated during the cutting or trimming of the wall-paper, and for guiding the cutting device along an adjacent length of wood-work or a meeting wall disposed at either side of the cutting blade. This assembly comprises a circular bushing 15 on the end of the handle 11 from which the blade holder 12 extends. The bushing 15 is formed with a pair of axially spaced apart, radial flanges 16 and 17 defining an outwardly opening, annular channel therebetween. A support and guide member 18 is swingably mounted in the channel defined between the flanges 16 and 17, and includes a split ring-like part 19 having legs 20 and 21 extending from the ends thereof and engaging slidably between the flanges 16 and 17. The legs 20 and 21 are bowed outwardly intermediate their lengths (Fig. 2) to conform to the circumferential configuration of the annular channel between the flanges 16 and 17 so that the support and guide member 18 may be swung as in Figs. 5, 6 and 7 relative to the handle 11 and blade holder 12 but is restrained from radial displacement relative to the latter by the engagement of the bowed parts of the legs 20 and 21 in the annular channel of the bushing 15. A locking link 22 is formed with loops on its opposite ends which extend around the free end 40 portions of the legs 20 and 21 to prevent spreading apart of the latter and disengagement of the member 18 from the bushing 15.

In order to limit the swinging movement of the support and guide member 18 relative to the blade holder 12, the flanges 16 and 17 are pinched together at diametrically opposed locations, as at 23 and 24 (Figs. 3 and 4), to restrict the channel formed between the flanges. Thus, when the member 18 is swung in one direction, as in Figs. 5 and 7, the leg 20 will be stopped by the restriction 23 and the leg 21 will be stopped by the restriction 24. Conversely, when the member 18 is swung in the opposite direction, as in Fig. 6, leg 21 is stopped by the restriction 23 and leg 20 is stopped by the restriction 24.

As is apparent from Figs. 1 and 8, the ring-like part 19 of the member 18 lies in a plane which is angularly disposed relative to the legs 20 and 21 and the part 19 is dimensioned so that it engages the wall-paper being cut, and is normal thereto, when the forward end of the cutting blade 13 engages the paper (Fig. 8).

Referring to Figs. 6, 7 and 8, an appreciation of the manner of using the above described device, and its advantages, may be obtained. In Fig. 6, the wall-paper 25 has been applied to a wall 26, and it is desired to trim the paper along a length of wood-work or a meeting wall 27 which is to the right of the edge being trimmed as shown. The support and guide member 18 is positioned for cutting in that situation by swinging relative to the blade holder 12 in the direction away from the guiding wood-work or meeting wall 27 so that, with the ring-like part 19 engaging both

the wall 26 and the wood-work or meeting wall 27, the cutting blade 13 is disposed close to the latter for trimming the paper 25 substantially in the corner.

The engagement of the ring-like part 19 with the paper on the wall 26 supports the cutting blade relative to the latter so that the wall will not be penetrated or damaged during the trimming of the paper, while the simultaneous engagement of the ring-like part 19 with the wood-work or meeting wall 27 causes the latter to guide the blade during the cutting stroke. The ring-like configuration of part 19 permits engagement thereof with the wall 26 and the meeting wall 27 without forcing the paper in the immediate area being cut against the wall. Thus, the cutting blade may cut through the paper without dulling contact with the underlying wall or the guiding wood-work or meeting wall (Fig. 8).

When the guiding wood-work or meeting wall is disposed at the other side of the cutting device, as in Fig. 7, the support and guide member is again rocked relative to the blade holder, this time toward the right as viewed in Fig. 7, so that the cutting blade is once again positioned to trim the edge of the wall paper 25' along a line in the corner formed by the wall 26' and the guiding wood-work or meeting wall 27'.

From the above description it can be seen that the present invention provides a cutting device which may be used in trimming the edges of wall-paper and the like along the top, bottom or either side thereof.

While I have illustrated and described in detail a preferred embodiment of my invention, it is to be understood that I do not desire to be limited to the precise embodiment and that many changes and modifications, obvious to one skilled in the art, may be made therein without departing from the spirit and scope of the invention as defined in the appended claims.

What I claim is:

1. A wall-paper cutting device comprising a handle, a blade holder extending from an end of said handle and at an angle to the longitudinal axis of the latter, a cutting blade in said holder with its cutting edge exposed along one side of the latter, a substantially ring-shaped support and guide member extending from said handle at the end of the latter, adjacent said holder and in the direction of said exposed cutting edge, said ring-shaped support and guide member extending further from said longitudinal axis of the handle than said exposed cutting edge of the blade for tangential contact with wall-paper in a corner defined between a wall and a piece of trim along which the paper is to be cut so that the paper may stand away from the corner and be severed by said blade without requiring contact of the latter with the wall and trim, means mounting said ring-shaped support and guide member swingably on said handle for lateral displacement relative to said blade, and means limiting the swinging movement of said ring-shaped member relative to said handle so that said member may be disposed to position said blade for cutting wall-paper at a corner defined by the underlying wall and trim extending from the wall at either side of the device.

2. A wall-paper cutting device comprising a handle, a blade holder extending longitudinally from one end of said handle, a cutting blade in said holder with its cutting edge exposed along a longitudinal edge of the latter, a bushing mem-

ber on said one end of said handle having a pair of axially spaced radial flanges defining an annular channel therebetween, and a guide and support assembly including a split, substantially ring-shaped support and guide member having substantially parallel legs extending from the ends thereof and slidably through said annular channel of the bushing member at diametrically opposed portions of the latter so that said ring-shaped member may be rocked laterally relative to said handle and means holding said legs together within said channel.

3. A wall-paper cutting device as set forth in claim 2, including pinched together portions on said flanges at diametrically opposed locations

10

15

between said legs so that the rocking movement of said ring-shaped member is limited in both directions by engagement of said legs with said pinched together portions of the flanges.
